WASHING MACHINE

Warren O. Manley, North Kansas City, Mo., assignor, by direct and mesne assignments, to C. Earl Hovey, trustee, Kansas City, Mo.

Application November 10, 1944, Serial No. 562,754

5 Claims. (Cl. 68—173)

1

This invention relates to laundry equipment in the nature of a washing machine including as a component part thereof, a specially designed tub having motivating structure associated therewith for oscillating the same about an axis disposed with particular regard to the material dumping openings formed at each end of the tub.

One of the primary aims of this invention is to provide a washing machine for handling clothes or the like, which has as a part thereof not only the aforesaid specially positioned openings for shiftable means within the tub for selectively holding articles therein while liquid is poured from the tub as its substantially flat bottom is held at an angle to the horizontal by the driving means.

A still further object of this invention is to provide a washing machine with a tub that is equipped with a number of openings, through which the liquid or solid articles in the tub, may be selectively passed through the employment of the action of gravity.

Other objects of the invention include the precise form of the tub; the driving means therefor; the special manner of providing a mounting for the tub; and the several manually controllable actuating elements for moving the aforesaid shiftable means and the closures for the several openings to and from a selected predetermined position.

Further aims of the invention will appear during the course of the following specification, referring to the accompanying drawing, wherein:

Fig. 1 is a top plan view of the washing machine made in accordance with the present invention.

Fig. 2 is a vertical longitudinal sectional view taken on line II—II of Fig. 1.

Fig. 3 is a vertical transverse sectional view taken on line III—III of Fig. 2; and

Fig. 4 is a fragmentary end elevational view illustrating the operating means and latch for one of the end closures.

The embodiment of the invention illustrated comprises a tub, broadly designated by the numeral 10. This tub is formed of sheet material and includes a substantially flat bottom 12, merging into upwardly and rearwardly curved end walls 14, side walls 16 and a top 18, wherein is formed an access opening 20, closable by door 22, hingedly mounted as at 24 and latched closed by suitable parts 26.

Arcuate end walls 14 of tub 10 continue inwardly and downwardly to present a pair of lips 28 which cooperate with the inner contour of the

2

tub in establishing figure eight paths of travel for the washing solution and the articles being cleansed.

Tub 10 is carried by frame work 38 including a transversely disposed shaft 32 secured to bottom 12 of tub 10 and journaled in bearings 34, forming a part of frame 38. This shaft 32 is at the medial line between ends 14 and permits tipping of tub 10 during operation.

10 Tracks 36 on the bottom wall 12 of tub 10, serve as reinforcing elements and friction plates for the hereinafter described mechanism.

Opening 38 formed in tub 10 at the zones of juncture between bottom 12 and arcuate end walls 14 are covered by closures 40, hingedly mounted as at 42 and latched in place by lock 44 when the washing machine is in use. Lock 44 has a handle 46 for manually moving the dogs of the lock from the position shown in Figs. 2 and 4 to a location where they do not engage the respective closure 40—thus, when tub 10 is in the position shown in dotted lines of Fig. 2, for example, the contents of tub 10 may be emptied from the interior of the tub through the opening 38 at the left thereof, as viewed in Fig. 2.

15 A partition 48 swingably disposed within tub 10, is made of foraminous material or provided with a sufficient number of perforations to allow water to quickly traverse the partition when it is in the position shown in full lines of Fig. 2. In this position stops 50 preclude movement about the shaft 32 upon which partition 48 is hung. A manually manipulable lever 54 permits swinging partition 48 to the dotted line position (Fig. 2), when the tub is being tipped during normal use. This lever 54 has a "past center" action including a spring 56 and pintle 58 of conventional character to insure that partition 48 is yieldably maintained in either one of the two positions illustrated in the drawing.

20 Actuating mechanism for tub 10 is positive in that cams 60 mounted on transverse shafts 62 on each side of the axis of oscillation 32 always engage tracks 36. There is a pair of cams 60 on each side of shaft 32 and shafts 62 that mount cams 60 are synchronized to a connecting sprocket chain 64. One of shafts 62 is operably joined to motor 66 through a conventional speed reducer 68, if such be desirable. Obviously, shafts 62 are journaled for rotation in bearings 70 on frame 38 and the cams are so timed as to insure constant interengagement between their peripheries and the respective tracks 36.

25 During operation of the washing machine above described and illustrated in the accom-

panying drawing, tub 10 is tipped about shaft 32 by cams 60 and the contents thereof is thrown through paths of travel established by curved end walls 14 and the lips 28 thereof. These figure eight paths insure positive distribution of the soap or other detergent in the wash water and the clothes being treated are separated to such an extent that a quick and efficient first-wash and rinse is assured. During this washing operation, partition 48 is in the position shown in 10 dotted lines of Fig. 2. When washing has been completed and the water is to be emptied from tub 10, it is stopped in its movement with the bottom 12 downwardly inclined toward a trough 72 adapted to receive waste water and convey it to a drain. In this position, closure 40 is released by manipulating its lock 44 whereupon the same will swing open and allow the water to flow through opening 38.

Partition 48 has previously been dropped to the position shown in full lines of Fig. 2 while all of the articles in tub 10 were in the righthand portion of the tub and as it was in a position to so hold the articles through the action of gravity. Obviously, partition 48 will hold the articles against escape through the lowermost opening 38 as water is rushing into drain 72. Stops 50 receive the load and therefore, no tendency on the part of partition 48 to move while the liquid is being drained is present.

The articles are removed with speed and dispatch from tub 10, by merely tipping the tub in the opposite direction or to an angle where opening 38 in the righthand end of tub 10 is low enough to allow the articles to slide by gravity along bottom 12 and thence out through opening 38. Lock 44 is first manipulated to permit closure 40 to swing to the open position.

Partition 48 is disposed to one side of the center of tub 10 to the end that the mass of articles being washed may be collected to that side of the partition having the greatest volume and yet leave sufficient room for the partition to swing from the dotted line position shown in Fig. 2.

It may be desirable to eliminate partition 48 and if so, the opening 38 through which the cleansing solution is drained, may comprise a number of small openings or a foraminous inner shell that precludes the escape of solid articles, such as clothing, when the tub is tipped to the dotted line position shown in Fig. 2, for the purpose of emptying water therefrom.

The bottom 12 of tub 10 has a pair of ribs 76 disposed at each of its end zones to act upon the contents of the tub as it is moved through the figure eight paths of travel. The clothes being washed will impinge upon these end zones as tub 10 is rocked about the axis of shaft 32, whereupon lateral movement is imparted thereto. This lateral movement is with respect to the longitudinal central axis of tub 10 for the ribs 76 are in V-shaped patterns with the apexes directed toward the same end of tub 10. Obviously, as the clothes travel toward the ends, the respective sets of ribs 76 will move them toward and from the center of the tub. Ribs 76 must be relatively short with respect to the length of the flat bottom 12 of tub 10 in order to accomplish the desired result.

Washing machines having physical characteristics different from those illustrated and described might be made to embody the instant invention without departing from the scope of the appended claims.

Having thus described the invention, what is claimed as new and desired to be secured by Letters Patent is:

1. A washing machine comprising a tub having an opening in each end thereof adjacent to the bottom of the tub; doors for the openings; a shiftable partition within the tub for dividing the interior thereof into two compartments, each having one of the openings in communication therewith; and mechanism for holding the tub at angles of inclination where the action of gravity may move the contents of the tub through one of the openings.

15 2. A washing machine comprising a tub having an opening in each end thereof adjacent to the bottom of the tub; doors for the openings; a shiftable partition within the tub for dividing the interior thereof into two compartments, each having one of the openings in communication therewith; and mechanism for holding the tub at angles of inclination where the action of gravity may move the contents of the tub through one of the openings, said partition being provided with perforations permitting flow of liquid from 25 one side of the partition to the other.

3. A washing machine comprising a tub having an opening in each end thereof adjacent to the bottom of the tub; doors for the openings; a shiftable partition within the tub for dividing the interior thereof into two compartments, each having one of the openings in communication therewith; and mechanism for holding the tub at angles of inclination where the action of gravity may move the contents of the tub through one of the openings, said partition being provided with perforations permitting flow of liquid from 35 one side of the partition to the other, said partition having parts exterior of the tub for swinging the partition to and from the normal position forming said two compartments in the tub.

40 4. In a washing machine, a tub having a flat bottom; structure adapted to support the tub for tipping, oscillating motion about a transverse axis on the median line of the tub substantially in the plane of the bottom thereof, and means for moving the tub about said axis comprising cams on each side of the axis, power-applying means in connection with the cams, said cams being formed and disposed to maintain constant frictional contact with the bottom of the tub as it is tipped, and tracks on the outermost face of said bottom of the tub for receiving said cams.

45 5. A washing machine comprising a tub having an opening in each end thereof adjacent to the bottom of the tub; doors for the openings; a shiftable partition within the tub for dividing the interior thereof into two compartments, each having one of the openings in communication therewith; and mechanism for holding the tub at angles of inclination where the action of gravity may move the contents of the tub through one of the openings, said partition being provided with perforations permitting flow of liquid from 50 one side of the partition to the other, said partition having parts exterior of the tub for swinging the partition to and from the normal position forming said two compartments in the tub, said parts including means for yieldably holding said partition in either said normal position or in an inoperative position placing said compartments in unobstructed communication.
